UNITED STATES PATENT OFFICE.

FREDERICK MOENCH, OF RUSHVILLE, ILLINOIS.

AIR-COOLED MOTOR.

1,165,339.

Specification of Letters Patent. Patented Dec. 21, 1915.

Application filed April 29, 1915. Serial No. 24,688.

To all whom it may concern:

Be it known that I, FREDERICK MOENCH, a citizen of the United States, and a resident of Rushville, in the county of Schuyler 5 and State of Illinois, have invented certain new and useful Improvements in Air-Cooled Motors, of which the following is a specification.

My invention relates to improvements in 10 air cooled motors, and it consists in the combinations, constructions, and arrangements herein described and claimed.

An object of my invention is to provide a 15 motor of the internal combustion type which does not necessitate the use of water for cooling the same.

A further object of my invention is to 20 provide a device of the type described which is of light weight, owing to the use of aluminum for the radiating surface.

A further object of my invention is to provide a motor or engine having means for rapidly radiating the heat developed on the interior of its cylinders owing to the novel 25 construction whereby aluminum forms the greater part of the heat radiating and conducting medium.

Other objects and advantages will appear 30 in the following specification, and the novel features of the invention will be particularly pointed out in the appended claims.

My invention is illustrated in the accompanying drawings forming part of this application, in which—

35 Figure 1 is a perspective view of a motor constructed according to my invention. Fig. 2 shows the cylinder core prior to the application of the aluminum radiating medium. Fig. 3 is a fragmentary sectional view through a portion of the device, and Fig. 4 is a section along the line 4—4 of Fig. 3.

The invention is applicable to internal combustion engines of all types. In the 45 drawings I have illustrated an engine or motor of the so-called "valve in head" type. In carrying out my invention I provide a cylinder core 1 which is smooth on the inside and on the outside. Near one end of 50 the cylinder and adjacent to the compression space or chamber, I provide a series of perforations 2 extending through the walls of the core. In Fig. 3 I have shown the core provided with perforations and have also 55 indicated openings 3 and 4 for the valves,

an exhaust opening 5, and a spark plug opening 6. The arrangement of these openings is common and forms no part of my invention.

On the outside of the cylinder a coating 60 of aluminum is plated. This outside coating I have indicated at 7. The plating may be carried out by any suitable process, but I prefer to use that process described in my pending application Serial Number 20741 65 filed April 12, 1915. The cylinder core with its aluminum coating is then placed in a mold or form made of material of such a nature that it may be heated to 1400° Fahrenheit without disintegrating. This mold should be 70 heated and at the same time a sufficient quantity of pure aluminum should be heated to the melting point and then poured into the hot mold. The purpose of the mold is to form flanges like those shown at 8 on the 75 outer surface of the cylinder. The number of flanges and their depth will depend upon the radiation required. When the casting is removed from the mold, it should be left in the rough, since the rough surface insures 80 better radiation. The inside of the core is also plated with aluminum as shown at 9 in Fig. 3, as far as the compression chamber extends, and the inside plating is connected to the outside plating by a filling 9* of 85 aluminum in the openings 2.

In order to secure a maximum radiation, I plate the exhaust pipe 10 with a coating of 90 aluminum 11 having integral flanges 8* similar to the flanges 8. These flanges extend for several inches beyond the exhaust outlet 5.

An engine formed in accordance with my invention has two marked advantages over the ordinary engine. In the first place, the 95 radiation is such that no liquid cooling means is necessary, thus obviating a source of much trouble due to the clogging of the radiator pipe, leaking of the radiator or freezing or bursting of the radiator pipe, and also the liability of overheating the engine due to an insufficient supply of cooling liquid. A motor constructed in accordance with the present invention requires 100 little care as far as the radiation of heat is concerned. While sufficient heat radiation is secured, the motor as a whole is light in comparison with water cooled motors of the same power.

I am aware that air cooled motors having 110

radiating flanges are, broadly speaking, old, but the provision of a motor having an aluminum plating on the outside with integral aluminum flanges and aluminum plating on the inside connected by a series of aluminum heat conductors, I believe to be new and to present the merits heretofore mentioned.

I claim:

- 20 1. An internal combustion engine having a cylinder consisting of a cylindrical metal core having an outside plating of aluminum, a series of integral outwardly extending flanges carried by said aluminum plating, a plating of aluminum disposed within the cylinder core near one end of the cylinder, and an aluminum heating conducting bond between said outer and said inner aluminum plating.
- 20 2. An internal combustion engine comprising a cylindrical iron core provided with a series of perforations near one end, an outer plating of aluminum, an inner plating of aluminum near one end of the cylinder, heat conducting bonds of aluminum arranged to pass through the perforations in the iron core, and a series of integral out-

wardly extending aluminum heat radiating flanges carried by said outer plating.

3. An internal combustion engine comprising a cylindrical iron core having a series of perforations near one end, inner and outer platings of a relatively light metal of high heat conductivity, said inner and outer platings extending over a portion of the iron core. 35

4. An internal combustion engine comprising a cylindrical iron core having a series of perforations near one end, inner and outer platings of a relatively light metal of high heat conductivity, and heat radiating flanges carried by said outer plating. 40

5. An internal combustion engine comprising a cylindrical iron core having a series of perforations near one end, inner and outer platings of a relatively light metal of high heat conductivity, integral heat radiating flanges carried by said outer plating, and heat conducting bonds connecting said inner and said outer platings. 45

FREDERICK MOENCH.
